COMBINED COAT HANGER AND ICE SCRAPER FOR AUTOMOBILES

Edgar Derlein, Oostburg, Wis.

Application December 5, 1951, Serial No. 17,622

Term of patent 3½ years

(Cl. D9—6)

To all whom it may concern:

Be it known that I, Edgar Derlein, a citizen of the United States, residing at Oostburg, in the county of Sheboygan and State of Wisconsin, have invented a new, original, and ornamental Design for a Combined Coat Hanger and Ice Scraper for Automobiles, of which the following is a specification, reference being had to the accompanying drawing, forming part hereof.

Figure 1 is a side elevational view of a combined coat hanger and ice scraper for automobiles, showing my new design.

Figure 2 is a front elevational view of the same.

Figure 3 is a rear elevational view of the device.

Figure 4 is a top plan view of the device, and

Figure 5 is a bottom plan view of the device.

I claim:

The ornamental design for a combined coat hanger and ice scraper for automobiles, as shown.

EDGAR DERLEIN.
